UNITED STATES PATENT OFFICE.

FRANK BYCROFT KEALL, OF LEICESTER, ENGLAND, ASSIGNOR TO UNITED SHOE MACHINERY CORPORATION, OF PATERSON, NEW JERSEY, A CORPORATION OF NEW JERSEY.

PRESS.

Application filed January 25, 1924, Serial No. 688,453, and in Great Britain February 13, 1923.

This invention relates to presses and is illustrated as embodied in a press of the type utilized in cutting blanks from sheet material by the use of freely movable dies which 5 may be placed successively in selected positions on the material to be cut.

Presses commonly employed in cutting blanks from leather and other kinds of sheet material are known commercially as clicking machines. Such a machine is illustrated in United States Letters Patent No. 921,503, granted May 11, 1909 on application of Arthur Bates, and comprises a die block or other work supporting member and a presser 10 member having a pressure applying surface of an area considerably less than that of the die block. In the operation of the machine, the presser member is swung laterally over the die block into and out of operative relation to the die wherever the latter may be located on the work. In clicking machines as heretofore constructed, very considerable effort on the part of the operator was necessary to swing the presser member in moving 15 it into position over the die and subsequently in uncovering the die and the work so that the latter might be inspected and manipulated at will and the die repositioned on the work. While the greater part of the energy 20 expended by the operator in swinging the presser member was employed in overcoming the inertia of the relatively heavy presser member, an appreciable portion of the energy 25 required was accounted for in the friction between the presser member supporting post 30 and its bearings in the frame of the machine.

With this in view, it is an object of this invention to reduce the described friction to a minimum without sacrificing any of the 40 advantages of clicking machines of the aforesaid type. While the invention is applicable to many types of presses it is particularly intended for use with a clicking machine capable of heavy duty as regards cutting 45 through many layers of sheet material at a single operation, and having a cutting block and presser member each with unusually large pressure applying surfaces designed to provide a wide range of action in connection with the cutting of fabrics and other material of large surface dimensions.

In one aspect the invention resides in the provision of two sets of bearings for the

post, one set being movable and the other stationary,—one set operative during reciprocation of the post to cause a pressure applying operation by the presser member and the other set operative while the machine is at rest to maintain the post vertical and to serve as bearings while the presser member is 55 being swung in lateral directions over the work support.

In another aspect the invention resides in the provision of an auxiliary bearing means 60 for the presser member supporting post operative to maintain the latter in a vertical position while the presser member is being swung over the work support, and to facilitate such swinging movement.

In the illustrative machine, the auxiliary 70 bearing means is so constructed and arranged as to be thrown out of operation automatically when the post and pressure member start downwardly in a pressure applying operation so that the stationary bearings take 75 the lateral component of the stresses and strains which develop in the presser member and post during operation on the work.

Preferably and as shown the desired auxiliary bearing means is furnished by a plurality of bearings constructed to serve as anti-friction members and located on opposite sides of the post at a considerable distance 80 from each other so that one is located adjacent to the upper fixed bearing for the post 85 and the other adjacent to the lower fixed bearing for the post.

In the preferred construction, each anti-friction bearing comprises rollers spaced substantially 90° apart and movable downwardly 90 with the post in a manner to maintain engagement with the post without binding or wedging action thereon while the post is being supported by the fixed bearings during a pressure applying operation.

Other novel combinations of parts and features of construction will be described in the detailed specification and pointed out in the appended claims.

In the drawings:

Figure 1 is a side elevation, partly in section of a press embodying the invention in one form;

Figure 2 is a plan view, partly in section and to a larger scale, of the upper beam- 105 supporting bearing;

Figure 3 is an elevation, partly in section, showing one of the roller supports of the bearing;

Figure 4 is an elevation showing a cap of the bearing;

Figure 5 is a view similar to Figure 2 of the lower beam-supporting bearing;

Figure 6 is an elevation of one of the rollers and its supporting means of this bearing;

Figure 7 is an end view of a support for a roller arm of the lower bearing; and

Figure 8 is a side elevation partly in section of an alternative form of beam-supporting bearing.

The illustrative machine is of the general type of that described in the specification of Patent No. 921,503 aforementioned. The upstanding rear member 1 of the frame has the usual aligned upper and lower stationary bearings 2 and 3 for the beam-supporting post 4. These are however somewhat large in relation to the diameter of the post and when the post is in its raised position the latter is guided upon two auxiliary bearings respectively close to the upper and lower plain bearings.

The upper auxiliary bearing comprises a bracket 5 fixed to the front of the upper plain bearing 2. The bracket 5 has formed in it two recesses (one of which is shown at 6, Figure 3), in which are arms 7, 7 carrying rollers 8, 8 rotatably mounted on vertical pins 9, 9 fixed in the arms. The rollers 8, 8 track, at the front of the post 4, in a groove 10 formed in the post 4. The arms 7, 7 are pivoted on eccentric portions 11, of horizontal studs 12, 12 fixed in the bracket 5 by screws 13, so that by rotating the studs 12, 12 the rollers 8, 8 may be adjusted towards or from the post 4. The arms 7, 7 each have formed on them a cam face 14 which, when the post 4 falls and carries with it the rollers 8, 8, engages a face 15 formed on a plate 16, so as to hold the rollers in the groove 10. The plates 16, 16 are fixed by screws 17 to the bracket 5 and have threaded through them set-screws 18 by which the faces 15 may be adjusted towards or from the post 4.

The lower bearing comprises members 20, 20 fixed, at the rear of the post 4, by screws 21 in the frame 1. The members 20 have fixed in them horizontal pins 22, 22 on which are pivoted arms 23, 23 carrying rollers 24, 24 rotatably mounted on vertical pins 25, 25 fixed in the arms. The rollers 24 track in a groove 26 formed on the post 4. The rollers are adjustable towards and from the post by means of set screws 27 threaded through a flange 28 on the members 20 and bearing against the frame of the machine. The arms 23 have formed on them cam faces 29 which, when the post 4 falls, engage faces 30 on the members 20 and hold the rollers 24 in the groove 26.

As the post 4 descends the grooves 10, 26 draw the rollers 8, 24 down swinging the roller arms 7, 23 down and therefore causing the pressure of the rollers against the post to be relieved. The rollers therefore cease to have any beam-supporting function which is transferred to the plain but somewhat slack bearings 2, 3. The two rollers of each bearing are spaced apart 90° about the post axis and the angle between them is bisected by the vertical plane passing from front to back of the press through the middle of the press block and the post.

An alternative arrangement is one in which the displaceable roller bearings described are replaced by a fixed ball bearing 31 adjustably mounted on the frame 1 and having a tapered seat for a portion 32 of the post 4 to be borne thereby the said portion of the post being tapered in the same direction (i. e. it tapering towards the direction of rise of the post) so that as the post descends a slack is introduced between the tapered portion of the post and this auxiliary ball bearing support of the post being left to the plain bearings.

The upstanding rear member 1 of the frame has extending laterally at each side of it below the upper and lower bearings 2 and 3 a substantially cylindrical portion 33 which is bolted to a similarly shaped portion 34 extending laterally from a pair of side frames 35, the portions 33, 34 having intermeshing projections and recesses which prevent relative twist of the upstanding rear member 1 and side frames 35. The side frames 35 extend forwardly and at their inner sides are provided with lugs 36 carrying bearings 37 for vertical screwed posts 38 which support at each corner a rectangular bed 39 to which is fixed the cutting block 40. The screwed posts 38 have fixed on them sprocket wheels 41 round which passes a chain 42. Slack in the chain is taken up by an idler pulley (not shown) adjustably mounted on the under side of the bed 39. One of the screwed posts 38 has fixed on it a worm wheel 43 which meshes with a worm 44 fast on a horizontal shaft 45 extending from right to left of the machine rotatably mounted in bearings on the bed 39 and having fixed on its end a hand-wheel 46. When the hand-wheel is rotated the four screws at each corner of the bed will through the worm gearing and chain be equally rotated to raise or lower the cutting block.

Rolls of sheet material are placed in a tray 47 beneath the bed 39 and between the side frames 35, the tray being carried on wheels 48 so that it may be readily drawn out from under the bed to receive the rolls. The material in superimposed layers passes upwardly from the tray over the back of and on to the upper surface of the block 40. At the rear of the block just below and

parallel to its rear upper edge is a roller 49 over which the material passes. The roller is rotatably mounted in arms 50 at each end of the block pivoted on vertically 5 adjustable supports 51 fixed in the side frames 35. Springs 52 normally swing the arms and roller rearwardly to clamp the sheets of material against faces 53 formed on the upstanding frame member 1 to prevent the material from sliding back into the tray. When the operator desires to draw more material on to the block the roller 49 is swung forwardly to release the material by a hand lever 54 fixed to one of the arms 15 50 and locked in this position by the engagement of the lever with a pin 55 fixed in one of the side frames, the lever springing past the pin as it moves the roller forwardly and being held against the pin, 20 while the material is drawn over the block, by the springs 52 which clamp the material.

At the front of the cutting block is fixed a trough 56 into which scraps of material may be placed. The trough is open at one 25 end and a bag 57 is fixed on one of the side frames 35 into which the scrap falls as it is swept along the trough and out at the open end. Shields 58, 59 are provided between the side frames beneath the bed to 30 guide the material upwardly over the back of the cutting block and to prevent oil or dirt from falling on to the rolls of material in the tray.

In operating with the machine the presser member 60 is swung about the axis of the post 4 into a position at one side of the cutting block 40 so that a die may be readily positioned on the material 62 resting on the block 40. After the presser member has 40 been returned to position over the die the clutch (not shown) is tripped by depressing the handle 64 at the forward end of the lever 66 whereupon a pressure applying operation takes place during which the die is forced through the material. Subsequently, 45 pressure member 60 is again swung to one side to permit removal of the die and of the blank or blanks which have been cut from the material and to afford space for inspection of the material and repositioning of the die preliminarily to a repetition of the cutting operation.

Having thus described my invention, what I claim as new and desire to secure 50 by Letters Patent of the United States is:—

1. In a machine of the class described, a work supporting member and a presser member relatively movable toward and from each other in pressure applying operations 55 and also in directions laterally of each other, a post for supporting one of the members, and bearings for the post, some of the bearings being operative to maintain the post vertical while the machine is at rest and other bearings being operative to take the

lateral component of the stresses and strains which develop during a pressure applying operation.

2. In a machine of the class described, a work supporting member and a presser member relatively movable toward and from each other in pressure applying operations and also in directions laterally of each other, a post for supporting one of the members, and auxiliary bearings spaced from each other and at different levels on opposite sides of the post for maintaining the post in vertical position while the post is at rest at one limit of its movement and for facilitating swinging movement of the post, said auxiliary bearings being expansible to release the post.

3. In a machine of the class described, a work supporting member and a presser member relatively movable toward and from each other in pressure applying operations and also in directions laterally of each other, a post for supporting one of the presser members, loosely fitting stationary bearings for the post operative during a pressure applying operation to support the post against the lateral thrust of the work, and auxiliary bearing means operative to maintain the post out of contact with the stationary bearings while the machine is at rest thereby reducing friction on the post to a minimum and thus facilitating swinging movement of the post and of the presser member, said auxiliary bearing means being automatically operative to release the post to the stationary bearings during reciprocation of the post.

4. In a machine of the class described, a work supporting member and a presser member relatively movable toward and from each other in pressure applying operations and also in directions laterally of each other, a post for supporting one of the presser members, loosely fitting stationary bearings for the post operative to take the lateral thrust of the work during a presser applying operation, and auxiliary bearings for holding the post away from contact with the stationary bearings while the machine is at rest, each of said auxiliary bearings being pivoted to turn on a horizontal axis whereby it is automatically thrown out of operation when the post starts downwardly to apply pressure to the work.

5. In a machine of the class described, a work supporting bed, a presser member movable toward and from the bed in pressure applying operations and also in directions laterally over the bed into and out of operative relation to work on the bed, a post for supporting the presser member, upper and lower stationary bearings for the post and auxiliary bearings for the post, one of which is located in front of the post and adjacent to the upper bearing and the other adjacent to the lower bearing and at the rear of the

post, said auxiliary bearings comprising pivoted members adapted to swing toward and from the post so that the auxiliary bearings may be expanded to release the post.

5 6. In a machine of the class described, a work supporting bed, a presser member movable toward and from the bed in pressure applying operations and also in directions laterally over the bed into and out of operative relation to work on the bed, a post for supporting the presser member, upper and lower stationary bearings for the post, said post having a circular groove adjacent to the 10 upper bearing, and an auxiliary bearing comprising a roller adapted to seat in the groove in the post and movable in a direction away from the axis of the post so as to release the post to the stationary bearings during its reciprocation.

15 7. In a machine of the class described, a work supporting bed, a presser member movable toward and from the bed in pressure applying operations and also in directions laterally over the bed into and out of operative 20 relation to work on the bed, a post for supporting the presser member, and two sets of bearings for the post, one set being movably mounted and operative to maintain the post vertical while the machine is at rest and the other set being stationary and operative to take the lateral component of the stresses and strains which develop during a pressure 25 applying operation.

30 8. In a machine of the class described, a work supporting bed, a presser member movable toward and from the bed in pressure applying operations and also in directions laterally over the bed into and out of operative 35 relation to work on the bed, a post for supporting the presser member, and antifriction bearings spaced from each other and at different levels on opposite sides of the post for maintaining the post in vertical position and for facilitating swinging movement of the presser member and post.

40 9. In a machine of the class described, a work supporting bed, a presser member movable toward and from the bed in pressure applying operations and also in directions laterally over the bed into and out of operative 45 relation to work on the bed, a post for supporting the presser member, stationary bearings for the post operative during a pressure applying operation to support the post against the lateral thrust of the work, and antifriction bearings operative to maintain the post away from contact with the stationary bearings while the machine is at rest thereby reducing friction on the post to a 50 minimum and thus facilitating swinging movement of the post and of the presser member.

55 10. In a machine of the class described, a work supporting bed, a presser member movable toward and from the bed in pressure

60 applying operations and also in directions laterally over the bed into and out of operative relation to work on the bed, a post for supporting the presser member, stationary 65 bearings for the post operative to take the lateral thrust of the work during a pressure applying operation, and antifriction bearings for holding the post away from contact with the stationary bearings while the machine is at rest and automatically thrown 70 out of operation when the post and presser member start downwardly to apply pressure to the work.

75 11. In a machine of the class described, a work supporting bed, a presser member movable toward and from the bed in pressure applying operations and also in directions laterally over the bed into and out of operative 80 relation to work on the bed, a post for supporting the presser member, upper and lower stationary bearings for the post, and antifriction bearings for the post, located on opposite sides of the post, one of which is adjacent to the upper bearing and the other 85 adjacent to the lower bearing.

90 12. In a machine of the class described, a work supporting bed, a presser member movable toward and from the bed in pressure applying operations and also in directions laterally over the bed into and out of operative 95 relation to work on the bed, a post for supporting the presser member, upper and lower stationary bearings for the post, said post having a circular groove adjacent to the upper bearing and a similar groove 100 adjacent to the lower bearing, and antifriction bearings comprising rollers adapted to seat in the grooves in the post and movable in a vertical direction to maintain contact with the post during reciprocation of the 105 latter.

110 13. In a machine of the class described, a work supporting bed, a presser member movable toward and from the bed in pressure applying operations and also in directions laterally over the bed into and out of operative 115 relation to work on the bed, a post for supporting the presser member, said post having a circular groove, and an antifriction bearing for the post comprising a roller 120 adapted to seat itself in the groove, said roller being pivotally mounted so that it may move in a vertical direction to maintain contact with the groove in the post during reciprocation of the latter.

125 14. In a machine of the class described, a work supporting bed, a presser member movable toward and from the bed in pressure applying operations and also in directions laterally over the bed into and out of operative 130 relation to work on the bed, a post for supporting the presser member, and an antifriction bearing for the post comprising a roller mounted to turn about a vertical axis parallel to the axis of the post whereby 135

rotative movement of the post is facilitated.

15. In a machine of the class described, a work supporting bed, a presser member movable toward and from the bed in pressure applying operations and also in directions laterally over the bed into and out of operative relation to work on the bed, a post for supporting the presser member, and an antifriction bearing for the post comprising 40 two rollers spaced substantially 90° apart and each rotatable about a vertical axis parallel with the axis of the post so that rotation of the latter is facilitated.

16. In a machine of the class described, 45 a work supporting bed, a presser member movable toward and from the bed in pressure applying operations and also in directions laterally over the bed into and out of operative relation to work on the bed, a post 50 for supporting the presser member, stationary bearings for the post adapted to take the lateral thrust of the work during a pressure applying operation, and an antifriction bearing for the post adapted to hold the post 55 away from the stationary bearings while the machine is at rest thereby facilitating swinging movement of the post and of the presser member, said antifriction bearing automatically releasing the post when the latter starts downwardly in an operation of the machine.

17. In a machine of the class described, 60 a work supporting bed, a presser member movable toward and from the bed in pressure applying operations and also in directions laterally over the bed into and out of operative relation to work on the bed, a post 65

for supporting the presser member, side frames for supporting the bed extending from front to rear of the machine, and a C-shaped frame for supporting the post, said frame and said side frames having hollow cylindrical clamping portions coaxially arranged.

18. In a machine of the class described, 45 a work supporting bed, a presser member movable toward and from the bed in pressure applying operations and also in directions laterally over the bed into and out of operative relation to work on the bed, a post 50 for supporting the presser member, a holder for material located below the bed, members for guiding the material drawn upwardly at the rear of the bed, and a spring clamp for holding the material in position 55 on the upper surface of the bed.

19. In a machine of the class described, 60 a work supporting member and a presser member relatively movable toward and from each other in pressure applying operations 65 and also in directions laterally of each other, a post for supporting one of the members, and bearings spaced from each other and at different levels on opposite sides of the post for maintaining the post in vertical position 70 while the post is positioned at one limit of its movement and for facilitating swinging movement of the post, said bearings being expansible to release the post during pressure applying operations.

In testimony whereof I have signed my name to this specification.

FRANK BYCROFT KEALL.
